UNITED STATES PATENT OFFICE

106,200

DESIGN FOR A BOX

Andre Janer, Flushing, N. Y.

Application December 15, 1936, Serial No. 66,538

Term of patent 3½ years

To all whom it may concern:

Be it known that I, Andre Janer, a citizen of the United States and resident of Flushing, in Queens County, State of New York, have invented a new, original, and ornamental Design for a Box, of which the following is a specification, reference being had to the accompanying drawing forming a part thereof.

In the drawing:

Fig. 2 is a side elevation thereof.

The opposite side of the box is of duplicate appearance to the illustrated showings.

I claim:

The ornamental design for a box, as shown and described.

ANDRE JANER.
